UNITED STATES PATENT OFFICE.

PERCY B. BALL, OF WALLINGFORD, CONNECTICUT, ASSIGNOR TO R. WALLACE & SONS MFG. CO., OF WALLINGFORD, CONNECTICUT, A CORPORATION.

DESIGN FOR A HAND MIRROR OR SIMILAR ARTICLE.

Application filed November 6, 1926. Serial No. 19,631. Term of patent 14 years.

To all whom it may concern:

Be it known that I, Percy B. Ball, a citizen of the United States, residing at Wallingford, in the county of New Haven and State of Connecticut, have invented a new, original, and ornamental Design for a Hand Mirror or Similar Article, of which the following is a specification, reference being had to the accompanying drawing, forming part thereof.

I claim:

The ornamental design for a hand mirror or similar article as shown.

PERCY B. BALL.
